(57) **CLAIM**

The ornamental design for a knitting needle, as shown and described.

DESCRIPTION

FIG. 1 is an isometric view of a first embodiment of the present invention, including the word hope;

FIG. 2 is a front view of the invention of FIG. 1;

FIG. 3 is a top view of the invention of FIG. 1;

FIG. 4 is a bottom view of the invention of FIG. 1;

FIG. 5 is a rear view of the invention of FIG. 1;

FIG. 6 is a left end view of the invention of FIG. 1;

FIG. 7 is a right end view of the invention of FIG. 1;

FIG. 8 is an isometric view of a second embodiment of the present invention, including the word calm;

FIG. 9 is a front view of the invention of FIG. 8;

FIG. 10 is a top view of the invention of FIG. 8;

FIG. 11 is a bottom view of the invention of FIG. 8;

FIG. 12 is a rear view of the invention of FIG. 8;

FIG. 13 is a left end view of the invention of FIG. 8;

FIG. 14 is a right end view of the invention of FIG. 8;

FIG. 15 is an isometric view of a third embodiment of the present invention, including the word love;

FIG. 16 is a front view of the invention of FIG. 15;

FIG. 17 is a top view of the invention of FIG. 15;

FIG. 18 is a bottom view of the invention of FIG. 15;

FIG. 19 is a rear view of the invention of FIG. 15;

FIG. 20 is a left end view of the invention of FIG. 15;

FIG. 21 is a right end view of the invention of FIG. 15;

FIG. 22 is an isometric view of a fourth embodiment of the present invention, including the word patience;

FIG. 23 is a front view of the invention of FIG. 22;

FIG. 24 is a top view of the invention of FIG. 22;

FIG. 25 is a bottom view of the invention of FIG. 22;

FIG. 26 is a rear view of the invention of FIG. 22;

FIG. 27 is a left end view of the invention of FIG. 22;

FIG. 28 is a right end view of the invention of FIG. 22;

FIG. 29 is an enlarged detail view of the selected portion of FIG. 2;

(Continued)

FIG. 30 is an enlarged detail view of the selected portion of FIG. 9;

FIG. 31 is an enlarged detail view of the selected portion of FIG. 16; and,

FIG. 32 is an enlarged detail view of the selected portion of FIG. 23.

Portions of the drawings in broken lines are not included in the protected design. The long dashed lines shown between the knitting needle in FIGS. 1-5, 8-12, 15-19 and 22-26 depict symbolic break lines and form no part of the claimed design.

1 Claim, 9 Drawing Sheets
